MATTRESS RETAINER

Filed May 13, 1929

Inventor
Nathaniel Goldberg.

By
F. V. Winter,
Attorney

UNITED STATES PATENT OFFICE

NATHANIEL GOLDBERG, OF BROOKLYN, NEW YORK

MATTRESS RETAINER.

Application filed May 13, 1929. Serial No. 362,670.

This invention relates to the general art of bedding, and the improvements are directed to novel and unique means for retaining a mattress in position on a bed spring.

As will presently appear the device is adapted to form the opposite longitudinal sides of a bed-spring, or the like, a portion thereof being coupled to an ordinary spring and another section to the transverse end

10 frame members of the former.

An essential feature of the invention resides in the provision of a device of the above-mentioned character which is formed from a single piece of relatively light guage metal, the same being bent to form a tubular portion adapted for intimate contact with a mattress and having an upstanding and horizontal portion of double-thickness wherein the necessary rigidity and strength is secured.

Another object of the invention is the provision of a tubular portion, which is positioned at a somewhat elevated point above said horizontal portion, said tubular portion being presented to both longitudinal sides of a mattress in a manner to preclude the shifting or displacement of the latter at all times.

A still further object is to provide an upstanding portion which functions in the nature of a web in order to strengthen the construction as a whole and thus to withstand abnormal loads placed on or adjacent the edge of a mattress or spring.

Still another object of the invention is to provide a device of the above character which is admirably adapted to maintain a mattress in non-shiftable position and at the same time to serve as a support for the sides and marginal edge portions thereof.

With these objects in view, together with others which will appear as the description proceeds, the invention resides in the novel formation, combination and arrangement of parts, all as will be described more fully hereinafter, illustrated in the drawings, and particularly pointed out in the claims.

In said drawings:

Figure 1 is a plan view of a typical bed spring equipped with my invention, the

spring portion being shown somewhat diagrammatically.

Fig. 2 is a transverse sectional view taken substantially on the line 2—2 of Fig. 1, the mattress being shown in outline.

55

Fig. 3 is an enlarged transverse section through one of the retainers; and

Fig. 4 is a similar view of a slightly modified form.

Referring now more in particular to the accompanying drawings, wherein like characters of reference denote similar parts throughout the several views, let 5 indicate generally a bed-spring, the same including the usual frame members 6 and 7 which support the spring 8. In Figure 1, of the drawings, the spring 8 has been shown diagrammatically since no special link formation is anticipated for incorporation with the invention.

The retainers, forming the subject-matter of the present invention, are designated by the numeral 9, and as shown in Fig. 1, are each adapted to be positioned along the opposite longitudinal sides of a spring, the connection between said retainers and said spring being preferably in the form of coiled springs 10, which extend from said frame members 6 and 7, the opposite end of each of said springs being suitably coupled to said retainers. As shown in Figs. 2 and 3, each of the retainers are formed from a single piece of light gauge metal, said piece of material being formed to provide a tubular portion 11, an upstanding portion 12 and a horizontal or flange portion 13, said upstanding and horizontal portions being of double thickness in order to provide the requisite strength and rigidity, as will be well understood.

When said retainers are combined with the other parts of a bed-spring, as aforesaid, it will be seen that the tubular portion 11 of each of the retainers, snugly abut the sides of a mattress 14; and, as a matter of fact, said tubular portions force themselves partially into the sides of said mattress, (see Fig. 2), so that the latter is firmly anchored to the spring and lateral displacement utterly precluded. It will also be noted that said upstanding

100

portion 12 engages the sides of the mattress, while the horizontal flange 13 serves as a support for the opposite marginal edges of said mattress. Thus the tubular portions, and 5 also the upstanding and horizontal portions mutually combine to form a structure whereby the mattress is positively retained in position under all conditions and circumstances.

As shown in Fig. 3, the corner between the 10 upstanding and horizontal portions may be curved, as indicated at 15, or the corner may be sharp, more or less, as shown at 16 in Fig. 4. In all other respects the forms shown in Figs. 3 and 4 are similar.

15 The inner edge of each of the horizontal flanges 13 may be apertured, as shown at 17 for the reception of connectors from the spring 8, and as shown in Fig. 1, the extremities of the tubular portions 11 may be flattened and apertured, if desired, to facilitate attachment to the springs 10. Obviously, 20 the method of attachment is not essential, so long as a strong structure is developed.

From the foregoing it is apparent that I 25 have devised a retainer which is formed from a single piece of material, formed in a manner to produce a tubular portion adapted to be embedded in the sides of a mattress and at the same time having upstanding and horizontal portions, of sufficient rigidity, to support the sides and marginal edge portions of a mattress.

While the present is a disclosure of the preferred embodiments of the invention, it is to 35 be understood that the same is not limited thereto, as various changes in the minor details of construction, proportion and arrangement of parts may be resorted to without departing from the spirit of the invention 40 as defined in the appended claims.

I claim:

1. A mattress retainer formed from a single piece of rigid material and including a tubular portion adapted to be embedded in the sides of a mattress, and having an upstanding flange and a horizontal flange the latter being adapted to support the longitudinal margin portion of the mattress.

2. A mattress retainer comprising a single piece of metallic material having a tubular portion adapted to be embedded in the sides of a mattress, and having an upstanding flange and a horizontal flange to engage the sides and longitudinal margin of said mattress.

In testimony whereof I affix my signature.
NATHANIEL GOLDBERG.
